Patented May 18, 1976

239,962

AUTOMATIC PLANT WATERING DEVICE OR SIMILAR ARTICLE

Paul S. Von Till, 115 Standford Ave.,
Colonia, N.J. 08817

Filed Mar. 20, 1974, Ser. No. 452,682

Term of patent 14 years

Int. Cl. D11—02

U.S. Cl. D35—3 R

Fig. 1.

Fig. 2.

Fig. 3.

Fig. 4.

Fig. 6.

Fig. 5.

FIG. 1 is a front perspective view of an automatic plant watering device or similar article showing my new design; the tubular support member is broken away to indicate indeterminate length;

FIG. 2 is a side elevation thereof;

FIG. 3 is a cross-section taken on line 3—3 of FIG. 2;

FIG. 4 is a second modified embodiment partially in cross-section, disclosed for clarity of illustration;

FIG. 5 is a third modified embodiment partially illustrated in cross-section; and

FIG. 6 is a top plan view thereof.

I claim:

The ornamental design for an automatic plant watering device or similar article, substantially as shown and described.
